UNITED STATES PATENT OFFICE.

OVID P. WELDING, OF SIOUX CITY, IOWA.

COMBINATION BUCKLE AND THILL-CARRIER.

No. 888,947.

Specification of Letters Patent.

Patented May 26, 1908.

Application filed June 13, 1907. Serial No. 378,755.

To all whom it may concern:

Be it known that I, OVID P. WELDING, a citizen of the United States, residing at Sioux City, in the county of Woodbury and State of 5 Iowa, have invented a new and useful Improvement in a Combination Buckle and Thill - Carrier, of which the following is a specification.

This invention relates to a combined thill 10 carrier and buckle designed to be carried by a harness and to be sold with the harness, thus reducing the number of parts and also affording a quick and improved manner of securing thills and the girth strap.

15 The invention consists also of the novel features of construction hereinafter fully described, pointed out in the claims and shown in the accompanying drawings, in which,

20 Figure 1 is a perspective view of the improvement, the thill being shown in position in dotted lines. Fig. 2 is a side elevation looking from the inner side. Fig. 3 is a section on the line 3—3 of Fig. 2.

In constructing the device I bend a piece of 25 wire, upon itself forming a bail A and adjacent the bow portion of this bail the said wire is bent upon itself to form two parallel eyes A' one upon each side member of the bail. These eyes are connected together by a trans- 30 verse bar A² formed of a piece of wire similar to that employed in making the bail, and which is bent to engage the eyes. The bow portion of the bail forms in combination with a tongue A³ pivotally carried by the bar A² a 35 buckle. The free end portions of the wire forming the bail A, diverge and are curved outwardly and upwardly and upon the bail is secured a thin metal plate B, the sides of which are cut and crimped around the curved

40 side members of the bail, thus forming a curved holder for the thill. To coöperate with this holder and lock the thill in engagement with it, I provide a second bail C also of wire, the free ends of which are bent to form 45 eyes C' which also engage the eyes A' thus pivotally connecting the two bails together and in reverse position with respect to each other. The bail C is bent transversely and carries a plate D formed of metal the sides of

50 which are crimped or bent around the side members of the bail C. A strap E is carried by the bow portion of the bail C and is designed to be buckled to the girth strap and a strap F is carried by the buckle above referred

55 to and is intended to be connected to a suitable strap from the harness saddle.

It will be obvious that when the strap E is unbuckled the plate D can be swung upwardly and outwardly permitting the thill to be readily removed from the holder formed 60 by the two bails and the two plates, and when the strap E is buckled to the girth or any strap substituted therefor, the bail C will be drawn toward the bail A and the thill locked in place. This construction also permits 65 the device to be employed in connection with thills of different diameters.

In connection with large wagons and for heavy loads the device may be made of heavy metal and it will also be obvious that 70 the bail C and plate D may, if desired, be formed in one piece and also that the bails A and C may be pivotally connected or hinged to each other in a number of different ways without changing the invention or affecting 75 the operation of the device.

Having thus fully described my invention, what I claim as new and desire to secure by Letters Patent, is:—

1. A device of the kind described comprising oppositely arranged bails, one of said bails having eyes formed upon its side members, the ends of the other bail being in engagement with said eyes, a tongue carried by one of said bails and a strap secured to the 85 other bail, the tongue projecting upwardly and the strap extending downwardly, as and for the purpose set forth.

2. A thill holder comprising two oppositely arranged bails, one of said bails having 90 eyes formed upon its side members adjacent its bow portion, the free ends of the other bail engaging said eyes, metal plates carried by said bails and bent to inclose a thill, and means for connecting straps to the bow portions of each of said bails.

3. A device of the kind described consisting of a wire bail, the side members of the bail being bent adjacent its bow portion to form eyes, a bar connecting said eyes, a 100 tongue carried by said bar and coöperating with the bow portion of the bail to form a buckle, a second bail having its free ends in engagement with the eyes of the first mentioned bail, and suitable straps connected to 105 each bail, as and for the purpose set forth.

OVID P. WELDING.
